*E. M. Shan,
Mortising Machine.*

Patented Mar. 23, 1836.

Mar 23, 1836

Charles M. Shaw of Woburn, Mass.,
Sellers, Patent.

The Schedule referred to in these Letters Patent andона the first of the same containing a description in the words of Charles C. Rogers of his own of his improvement, "in the horizontal Mortising machine for mortising and trimming timber."

Be it known that I, Charles M. Shaw of Woburn in the County of Middlesex State of Massachusetts, have invented a new and useful improvement in the machine for cutting Mortises and trimming called "Shaw's horizontal mortising machine," which is described as follows: referring to the annexed drawings of the same mortising part of the specification. This machine consists of a rectangular frame adapted in size and strength to receive and support the different parts of the machine to be hereinafter described and is marked A in the annexed drawing. The carriage B, is composed of a piece of timber in the form of a parallelogram which is made to slide to the right and left on the top of the frame previously described, and is held in its proper position by two plates C, C secured to the side of the frame and slipped over the carriage. In the centre of the carriage is made an opening to receive a slide D in which the mortising chisel or cutter E is fixed. To the under side of the slide is attached a lever F, for moving the slide by turning on a bolt or fulcrum G fixed to the lower side of the carriage, having an opening made thereto to admit the end H which connects the short end of the lever to the slide and a weight I is suspended to the short end of the lever to increase the force of the cutter. The cutter consists of an iron rod K passing thro' the slide and made fast in it by a square shoulder pin. The end of the rod near the timber to be mortised, is formed into a chisel or cutter, the other end has a crank handle L, for turning it and of the slide is formed into a triangular form M, for working the hands or fully, it rests upon the top of the carriage and each has an elongated mortise near its end working over a pin in the carriage; the other end working in a notch formed in the edge of the plate C against the end of each pull being a spring O, for throwing it back when released by the hands. A platform P, to support the timber to be mortised is placed upon the frame and can be regulated for different widths of timber to be mortised by means of stones or wedges, and the timber can be raised or lowered by passing a pin through the

Mar 23, 1836

bottom of this platform. The whole machine may be secured to the floor by means of screws, or other fastenings. The timber to be mortised is laid upon the platform and secured in its position by clamp screws. motion is then given to the slide which causes the cutter or cutter horizontally, by the lever which is moved by the hand up and down. the weight on the slide and giving force to the cutter when the lever is forced down the slide rotates and the man on it, and with the pull which moves the carriage with the cutter to whilst the timber remains stationary. when one cut is made the position of the cutter is changed, and the motion of the carriage reversed by throwing the second pull inward the first out of gear. the chips are drawn from the mortise by bearding the chips.

The invention here claimed, and desired to be secured by Letters Patent, consists in the arrangement and adaptation of the several parts of the machine for doing the one here described for mortising and tenoning timber, particularly the manner of operating the machine in causing the carriage to move to the right and left, whilst the slide with the cutter moves horizontally backward and forward at right angles to the carriage. I do not mean however to confine myself to any particular kind of material and dimensions of parts, intending to vary them as well as their arrangement in any manner to produce the effect intended without changing the principle of the machine.
